UNITED STATES PATENT OFFICE.

STEPHEN F. ELKINS, OF PITTSBURG, PENNSYLVANIA, ASSIGNOR TO THE MANUFACTURERS' SALES CO., OF PITTSBURG, PENNSYLVANIA.

SHADE-HOLDER FOR INVERTED GAS-BURNERS

960,630.

Specification of Letters Patent. Patented June 7, 1910.

Application filed November 16, 1909. Serial No. 528,383.

To all whom it may concern:

Be it known that I, STEPHEN F. ELKINS, a citizen of the United States, residing at Pittsburg, in the county of Allegheny and State 5 of Pennsylvania, have invented a new and useful Shade-Holder for Inverted Gas-Burners, of which the following is a specification.

The invention relates to improvements in shade holders for inverted gas burners.

10 The object of the present invention is to improve the construction of shade holders for inverted gas lamps, and to provide a simple, inexpensive and efficient supporting ring, adapted to support an outer shade and 15 an inner cylinder or chimney in spaced relation, and provided with means for permitting a free passage of air through the space between the outer shade and inner cylinder, whereby the brilliancy of the light is increased and the outer shade is maintained 20 sufficiently cool to prevent it from becoming broken through sudden drafts.

With these and other objects in view, the invention consists in the construction and 25 novel combination of parts hereinafter fully described, illustrated in the accompanying drawing, and pointed out in the claims here-to appended; it being understood that various changes in the form, proportion, size 30 and minor details of construction, within the scope of the claims, may be resorted to without departing from the spirit or sacrificing any of the advantages of the invention.

In the drawing:—Figure 1 is a vertical 35 sectional view of a shade holder, constructed in accordance with this invention and shown supporting an outer shade and an inner cylinder or chimney. Fig. 2 is a plan view of the same. Fig. 3 is a perspective view of 40 the shade holder.

Like numerals of reference designate corresponding parts in all the figures of the drawing.

In the embodiment of the invention illustrated in the accompanying drawing, the shade holder consists of a metallic supporting ring 1, constructed of a single piece of metal and provided intermediate of its top and bottom with an annular groove or indentation 2, adapted to be engaged by clamping screws 3 of a burner 4 into which the supporting ring fits in the ordinary manner. The supporting ring is provided at the bottom with an outwardly extending annular 55 flange 5, forming a seat for an outer shade

6, which may be of any preferred style or configuration. The supporting ring is inserted through the opening at the top of the outer shade from beneath, and when the supporting ring is applied to a burner, the shade will be firmly supported in its usual position.

The supporting ring is provided at the top with an inwardly extending annular flange 7, having an inner inclined portion 8, forming a seat for an inner cylinder or chimney 9, which is supported in spaced relation with the outer shade, as clearly illustrated in Fig. 1 of the drawing. The horizontal portion of the annular flange 7 is 70 provided with an annular series of vent apertures 10, adapted to permit the hot air to pass upward freely through the intervening space between the inner cylinder or chimney and the outer shade. The maintaining of an upward current of air through the said space and a constant changing of air between the outer shade and the inner cylinder prevents any accumulation of the heat produced by the burner, 80 and the outer shade is maintained in a relatively cool condition, so that there is no danger of its being broken through unequal expansion produced by sudden drafts of air on portions of it. Also the upward current 85 of air through the space between the inner cylinder and the outer shade prevents sudden drafts from striking the mantle and interfering with proper combustion.

The supporting ring is provided at intervals with integral tongues 11, extending upwardly and outwardly and engaging the upper edge of the outer shade, and adapted to maintain the same on the lower seat formed by the outwardly extending bottom 95 flange. The tongue engages the outer shade with sufficient force to sustain the supporting ring and the inner cylinder when handling the device by the outer shade in fitting the ring to and removing the same from a 100 burner.

Having thus fully described my invention, what I claim as new and desire to secure by Letters Patent, is:—

1. A shade holder consisting of a supporting ring provided with inner and outer seats spaced apart and arranged to receive the outer shade and an inner chimney or cylinder and spacing the same from each other, said ring being provided in its exterior 105

110

above the outer seat with an annular groove to receive the clamping means of a burner, and having vent apertures located at the top of the space between the shade and chimney and communicating directly with the exterior for permitting air to pass through the space between the outer shade and the inner chimney or cylinder.

2. A shade holder consisting of a ring provided with exterior means for supporting an outer shade and having an annular groove above the said means to receive the clamping devices of a burner, and having an inwardly extending flange forming a seat and arranged to hold a cylinder or chimney in spaced relation with the outer shade, said flange being also provided with apertures to permit the passage of air through the space between the outer shade and the inner chimney or cylinder.

3. A shade holder consisting of a ring provided with exterior means for supporting an outer shade and having an inwardly extending flange forming a seat and arranged to hold a chimney or cylinder in spaced relation with the outer shade, said flange being also provided with apertures to permit the passage of air through the space between the outer shade and the inner chimney or cylinder.

4. A shade holder consisting of a ring provided with exterior means for supporting an outer shade and having an inwardly extending annular flange composed of an outer horizontal portion and an inner inclined portion forming a seat for a chimney

or cylinder, the horizontal portion of the flange being provided with apertures to permit the air to pass freely between the outer shade and the inner chimney or cylinder.

5. A shade holder consisting of a supporting ring constructed of a single piece of metal and provided at the lower edge with an outwardly extending shade supporting flange and having an inwardly extending annular flange at the top, the inwardly extending flange being provided with an inner downwardly inclined portion to form a seat for a chimney or cylinder, the top flange being also provided with apertures to permit the passage of air through the ring.

6. A shade holder consisting of a supporting ring constructed of a single piece of metal and provided at its lower edge with an outwardly extending shade supporting flange and having an annular groove above the said flange to receive the clamping devices of a burner, said ring being also provided at the top with an inwardly extending annular flange having an inner downwardly inclined portion to form a seat for a chimney or cylinder, the top flange being also provided with apertures to permit the passage of air through the ring.

In testimony, that I claim the foregoing as my own, I have hereto affixed my signature in the presence of two witnesses.

STEPHEN F. ELKINS.
